The ornamental design for an electronic cigarette, as shown and described.

DESCRIPTION

FIG. 1 is a front elevational view of an electronic cigarette showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front, top, left perspective view thereof;

FIG. 8 is a rear, top, right perspective view thereof; and,

FIG. 9 is a rear, top, right perspective view of the electronic cigarette in another state.

The broken lines in the figures are included for the purpose of illustrating portions of the article which form no part of the claimed design.

1 Claim, 9 Drawing Sheets(56)
